UNDERREAMER

Application filed January 11, 1927. Serial No. 160,427.

Our invention relates to well drilling tools and more particularly to improvements in under-reamers.

It is an object of the invention to provide 5 a tool of this character having cutters rockably mounted in the body and a wedge for automatically expanding and holding the cutters solidly seated against the end of the body.

10 A further object of the invention is to provide a tool of the above-mentioned character having a socket in the lower end of the body to receive the rockable cutters, suspended from the wall of the socket by lugs, the wall 15 being provided with a plurality of slots to receive the lugs, whereby the cutters may be turned in the socket to change the position of their seat.

A further object of the invention is to provide 20 a tool of the above-mentioned character having a trip mechanism for moving and holding the expansion wedge in an inoperative position while the tool is being inserted or removed from the well.

25 Another object of the invention is to provide a tool of the above-mentioned character which is strong and durable in construction, reliable and efficient in operation and inexpensive to manufacture.

30 Other objects and advantages of the invention will be apparent during the course of the following description.

In the accompanying drawings, forming 35 a part of this specification and in which like numerals are employed to designate like parts throughout the same,

Fig. 1 is a front elevation of our improved under-reamer,

Fig. 2 is a longitudinal sectional view of 40 the same,

Fig. 3 is an enlarged fragmentary sectional view of the trip mechanism,

Fig. 4 is a cross section taken on lines 4-4 45 of Fig. 2,

Fig. 5 is a cross section taken on lines 5-5 50 of Fig. 2,

Fig. 6 is a cross section taken on line 6-6 55 of Fig. 2, and

Fig. 7 is a cross section taken on lines 7-7 60 of Fig. 2.

In the drawings, wherein for the purpose of illustration we have shown a preferred embodiment of our invention, the numeral 5, designates the reamer body which has an annular socket 6 in its lower end to receive the 55 shanks 7, of the cutters 8, as more clearly shown in Fig. 2. The cutters are substantially semi-circular in cross section and each is formed with a shoulder 9, on its outer face, approximately midway its length which 60 squarely abuts against the end of the socket when the cutters are in operative position. The shanks 7, of the cutters are provided adjacent their upper ends and centrally thereof, with outwardly projecting lugs 10, 65 adapted to loosely fit in slots 11 extending through the wall of the socket. The socket is provided with four of the slots 11, arranged around the wall at equal distances, permitting the cutters to be turned a quarter of a 70 turn when their seats become worn. When the cutters are in operative position the inner face of the shanks at the upper end are disposed on a plane parallel with the longitudinal axis of the body, as at 12, and from 75 the point 13, gradually incline downwardly at an angle to the longitudinal axis of the body, as at 12', the outer face of the cutters below the shoulder 9, being beveled at a corresponding angle, so the body of the cutters 80 will be of uniform thickness. Thus, it is seen that the cutters are capable of collapsing, so as to lie within the circumference of the reamer body and a wedge-shaped block 14, connected to the lower end of the mandrel 15 85 is adapted to spread or expand the cutters to cutting position. The mandrel 15, extends upwardly through the axially disposed bore 16 of the reamer body having an expansion spring 17 mounted thereon, one end of which 90 is seated on the shoulder 18, at the lower end of the bore and its other end bears against the end of the sleeve 19, threaded on the upper end of the mandrel, as at 19'. The spring 17, normally exerts an upward thrust upon 95 the mandrel causing the wedge block 14 to automatically expand and firmly hold the cutters in operative position. The inner face of the cutters is provided with a central longitudinal groove 20, to receive the mandrel 100

which prevents withdrawal of the cutters until the mandrel is removed. When the wedge block is withdrawn, the mandrel serves as a fulcrum for the upper end of the cutters, whereby the lower ends will automatically collapse.

The trip mechanism for holding the wedge block in an inoperative position, while the reamer is being inserted or removed from the well, as more clearly shown in Fig. 3, 10 consists of a pair of trips 21, adapted to slide in longitudinal grooves 22, in opposite sides of the reamer body, at a point adjacent the upper end of the mandrel. The surface 15 of the grooves intermediate their length have a gradual drop, as at 23, placing the lower portion of the grooves on a plane nearer the longitudinal axis of the body than the upper portion. The trips are connected together by 20 a cross bar 24, extending through slots 25 in the grooves 22, the trips being slidably on the ends of the bar and provided with transverse pins 26 extending through slots 27 in the ends thereof. The cross bar extends 25 through an opening 27' in the sleeve 19 and is normally seated on the upper end of the mandrel between the prongs 28, projecting upwardly therefrom. The cross bar is held 30 against transverse movement by the locking pin 29, threadedly mounted in the sleeve 19, as at 30, having its lower end bearing against the upper edge of the cross bar. Thus, it is seen that the cross bar 24, locks the sleeve and mandrel 15 against rotary movement, 35 maintaining the wedge block 14 in proper alignment with respect to the inner faces of the cutters, insuring free longitudinal movement of the mandrel.

The upper end of the body 5 is interiorly 40 threaded and tapered, as at 31, to receive the tapered threaded nipple 32 of the cap 33, the upper end of the cap being tapered and threaded, as at 34, for connecting the tool with the usual string of tools. The cap 33 has its 45 lower end recessed, as at 35, to receive the upper ends of the sleeve 19 and pin 29. The bottom of the block 14, has a screw-threaded recess 36, adapted to receive an eye bolt, not shown, to permit manual extraction of the 50 block.

In operation, when it is desired to insert the tool in a well, the wedge block is extracted, through the medium of an eye bolt, drawing the trips 21 downwardly into the lower portion 55 of the grooves 22 and compressing the coil spring 17. The trips are retained in the lower portion of the grooves by a clamping ring or other suitable device, well known in the art, until the reamer is inserted in the 60 well casing, whereupon the casing will retain the trips in place. When the reamer passes the lower end of the casing the trips are released and the upward thrust of the coil spring forces the mandrel upwardly, causing 65 the wedge block to expand the cutters and

solidly hold them in an operative position. The tension of the spring 17 is adjusted by the sleeve 19, threaded on the upper end of the mandrel and when the tool is assembled the cross bar 24, locks the mandrel and sleeve 70 against rotary movement, maintaining the wedge block in proper alignment to insure expansion of the cutters. When the tool is removed from the well, the lower edge of the casing engages the trips, forcing the mandrel 75 downwardly and releasing the wedge block, thus permitting the cutters to collapse.

It is to be understood that the form of our invention is to be taken as a preferred example of the same and that certain changes in 80 the shape, size and arrangement of the parts, may be made without departing from the spirit of the invention or the scope of the subjoined claims.

Having thus described our invention, we 85 claim:

1. In an under-reamer, the combination of a body, cutters mounted in said body, a mandrel disposed axially of said body having means for expanding said cutters, a spring 90 mounted on said mandrel, a sleeve threaded on the upper end of said mandrel for adjusting the tension of said spring, said sleeve having opposed transverse slots, a cross bar slidably mounted in said body and extending 95 through the slots in said sleeve, and trips connected with said cross bar for controlling the longitudinal movement of said mandrel.

2. In an under-reamer, the combination of a body, cutters mounted in said body, a mandrel disposed axially of said body having means for expanding said cutters, a spring mounted on said mandrel, a sleeve threaded on the upper end of said mandrel for adjusting the tension of said spring and a cross bar extending transversely through said sleeve and having connection with said mandrel, the ends of said cross bar being slidably mounted in slots through the walls of said body. 105

3. In an under-reamer, the combination of a body, cutters mounted in said body, a mandrel disposed axially of said body having means for expanding said cutters, a spring mounted on said mandrel, a sleeve threaded on the upper end of said mandrel for adjusting 110 the tension of said spring, a cross bar slidably mounted in said body extending transversely through said sleeve and having connection with said mandrel and a pin threaded in said sleeve having engagement with said cross bar to hold the same against lateral movement. 120

4. In an under-reamer, the combination of a body, cutters mounted in said body, a mandrel disposed axially of said body having means for expanding said cutters, spaced 125 prongs protruding from the upper end of said mandrel, a spring mounted on said mandrel, a sleeve threaded on the upper end of said mandrel for adjusting the tension of said 130

spring and a cross bar extending transversely through said body and sleeve adapted to seat on the upper end of the mandrel between said prongs.

In testimony whereof we affix our signatures.

SAMUEL L. HIGHFILL.
ROBERT P. MAYS.
